UNITED STATES PATENT OFFICE.

WESLEY A. THOMAS, OF MEMPHIS, TENNESSEE.

COMBINATION LADDER AND SEAT.

Application filed October 19, 1925. Serial No. 63,408.

The invention relates to combination ladders and seats, and has for its object to provide a device of this character which may be easily and quickly converted from a ladder to a seat or from a seat to a ladder, thereby allowing a ladder to be kept in position, when not in use where it can be easily used when desired as a ladder, and when not in use may be utilized as a seat, or a clothes drying rack.

A further object is to provide a ladder having a seat rigidly carried thereby at its upper end, and a supporting frame for the ladder which engages the underside of the platform of the ladder and has a link connection with the sides of the platform, thereby allowing the supporting frame to be positioned close to the ladder when the device is inverted and used as a seat, and positioned outwardly from the ladder when it is desired to support the ladder.

A further object is to provide U-shaped brackets carried by the inner sides of the frame bars which receive arms extending upwardly at the forward ends of the seat and which brackets brace the supporting frame when the device is used as a ladder.

A further object is to provide opposite sides of the seat with downwardly and rearwardly extending braces, the lower ends of which extend beyond the outer side of the platform of the ladder, and terminate in rollers whereby the device may be easily moved from place to place.

A further object is to provide bars at opposite sides of the platform, with which the linked end of the supporting frame engages when placed adjacent the ladder when the device is formed into a seat, or when positioned for supporting the device as a ladder, thereby rigidly bracing the structure as a whole.

With the above and other objects in view the invention resides in the combination and arrangement of parts as hereinafter set forth, shown in the drawing, described and claimed it being understood that changes in the precise embodiment of the invention may be made within the scope of what is claimed without departing from the spirit of the invention.

In the drawing:—

Figure 1 is a perspective view of the device showing the same in the form of a ladder.

Figure 2 is a side elevation of the device

showing the same in the form of a seat and the supporting frame for the ladder in dotted lines.

Figure 3 is a front elevation of the device.

Figure 4 is a horizontal sectional view taken on line 4—4 of Figure 2.

Figure 5 is a side elevation of the device, showing the same in position for use as a clothes drying rack.

Referring to the drawing, the numeral 1 designates the ladder, the upper end of which is provided with a platform 2, rigidly attached thereto, and which platform is provided with bars 3 at its opposite ends. The bars 3 are disposed outside of the sides of the ladder 1, the purpose of which will presently appear. Rigidly attached to the ladder 1 adjacent its upper end is a seat 4. The forward end of the seat is connected to the platform 2 by means of bars 6, which bars extend above the seat 4. The seat is further braced by the diagonal brace bars 7, which extend beyond the outer side of the platform 2 and engage the floor when the device is used as a seat and are provided with rollers 8, which allow the device to be easily moved from place to place, at which time the device is tilted on the rollers.

Pivoted to the bars 3 at 9 are links 10, which links are shown in turn pivoted at 11 to opposite sides of the supporting frame 12, which supports the ladder as clearly shown in Figure 1. The links 10 are of sufficient length, whereby when the supporting frame 12 is disposed adjacent the inner side of the ladder 1 as shown in Figure 2, the ends 13 of the bars of the supporting frame will engage the inner edges of the bars 3 of the platform, thereby thoroughly bracing the supporting frame 2.

Links 10 are also of sufficient length whereby when the supporting frame is moved to the dotted line position shown in Figure 2 preparatory to converting the device into a ladder, the U-shaped brackets 14 will receive the portions of the bars 6, which extend above the seat 4, and at the same time the ends 13 of the supporting frame bars 10 will engage the inner sides of the platform bars 3, thereby thoroughly bracing the supporting frame when the device is used as a ladder.

It will be seen that danger of movement of the supporting frame is obviated at all times, and the frame is positively braced and rigidly held. To further brace the lad-

der 1 and supporting frame 12, flexible members 15 are provided which are utilized as a clothes line when the device is inverted and used as a clothes drying rack.

5 The ladder 1 is provided with conventional forms of treads 16 and the supporting frame 12 with brace bars 17, however it is to be understood that the brace bars and treads may be of any construction desired 10 as well as the ladder and applicant does not limit himself to this particular construction, however the brace bars 17 are preferably wide and ornamental so as to conceal the ladder to a certain extent when the device is formed into a seat. When the device is 15 formed into a ladder the wheeled ends of the bars 7 may be utilized by the operator as handle members when climbing to the platform 2.

20 Referring to Figure 5, wherein the device is shown in a form whereby it may be used as a clothes drying rack, in this form the supporting legs 12 are raised and moved outwardly until the brackets 14 are received by the upper ends of the bars 6, and which bars, in connection with the links 10, which have been moved positively support the legs 12 at an angle where the flexible members 15 are maintained taut so that they may be 25 used as clothes lines on which articles may be hung for drying purposes.

30 From the above it will be seen that a combined ladder and seat is provided which is simple in construction, may be easily converted into a ladder or seat as desired, that a combined household article is provided which will allow a ladder to be maintained in a convenient position for use at all times, thereby obviating the storing of a ladder in 35 a basement or cellar.

The invention having been set forth what is claimed as new and useful is:—

1. The combination with a ladder having an angularly disposed platform, downwardly extending bars carried by the rear side of the platform, of a supporting frame for said ladder, said frame being provided with side bars, link connections between the side

bars and opposite sides of the platform and forming means whereby said frame may be 50 disposed adjacent the inner side of the ladder or spaced therefrom in engagement with the platform, and brackets carried by the side bars of the supporting frame and adapted to receive the downwardly extending bars of the platform. 55

2. The combination with a ladder having a platform angularly disposed at one end, a seat carried by said ladder below the platform, downwardly extending bars carried 60 by the platform at its rear side, forwardly and upwardly inclined brace bars at the sides of the seat and extending above the upper end of the ladder, rollers carried by the upper ends of the brace bars, of a supporting frame, said supporting frame comprising connected side bars at opposite sides of the seat, link connections between the platform and the side bars and forming 65 means whereby the side bars may be positioned adjacent the ladder or to the sides of the downwardly extending bars and brackets carried by the side bars and adapted to receive downwardly extending bars. 70

3. A combined ladder, seat, and clothes 75 drying rack comprising a ladder section, a seat carried by the ladder section, a supporting frame, a platform carried by the ladder and adapted to rest on a support, arms of the supporting frame having link 80 connections with the platform, upwardly extending bars and brackets carried by the supporting frame bars and adapted to be received by the upper ends of the upwardly 85 extending bars and in combination with the links supporting the frame a substantial distance from the ladder and flexible members carried by the supporting frame bars and the ladder and forming clothes receiving line when the device is used as a clothes 90 drying rack.

In witness whereof, I have hereunto set my hand at Memphis, Tennessee, this 28th day of September, 1925.

WESLEY A. THOMAS.
